UNITED STATES PATENT OFFICE.

OLIVER B. KEELEY, OF SPRING CITY, PENNSYLVANIA.

DESIGN FOR A COOKING-STOVE.

SPECIFICATION forming part of Design No. 12,696, dated January 17, 1882.

Application filed December 19, 1881. Term of patent 7 years.

To all whom it may concern:

Be it known that I, OLIVER B. KEELEY, a citizen of the United States, and a resident of Spring City, Chester county, Pennsylvania, have invented a Design for a Cooking-Stove, of which the following is specification.

My design for a cooking-stove is fully shown in the accompanying drawing.

A is the main oven-door, which has a flat border, *a*, with ornaments engraved and in relief, this border surrounding the central raised panel, *b*, the central ornament of which is a title-plate, *d*, with border *e*. Engraved ornamentation occupies the remainder of the panel. The end fire-place door, B, is substantially similar to the main door A, except that a monogram replaces the full title, and the border is without ornamentation. The door D has a flat border and a central raised panel with line-
20 engraving. The skirting E has a central enlarged portion with monogram-panel *f* and relief ornamentation *g* on each side of the same. The front fire-door, F, has two sets of oblong panels, *h*, one above the other and separated
25 by an inclined ledge with name-plate.

I claim—

1. The design for the doors A B, said design comprising the flat border *a* and raised panel *b*, having central title-plate, *d*, with border *e*, as shown and described. 30
2. The design for the skirting E, said design comprising the central enlarged portion with monogram-panel *f*, and the relief ornamentation *g* on the sides, as shown and described.
3. The design for the front fire-door, F, said design comprising the two sets of oblong panels *h*, separated by inclined ledge with name-plate, as shown and described. 35
4. The design comprising the doors A, B, D, and F and the skirting E, all ornamented as shown and described. 40

In testimony whereof I have signed my name to this specification in the presence of two subscribing witnesses.

OLIVER B. KEELEY.
